JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FILLING-DETECTOR MECHANISM.

1,372,084.

Specification of Letters Patent. Patented Mar. 22, 1921.

Application filed May 26, 1917. Serial No. 171,131.

To all whom it may concern:

Be it known that I, JONAS NORTHRUP, a citizen of the United States, residing at Hopedale, in the county of Worcester and State of Massachusetts, have invented certain new and useful Improvements in Filling-Detector Mechanisms; and I do hereby declare the following to be a full, clear, and exact description of the invention, such as will enable others skilled in the art to which it appertains to make and use the same.

The present invention relates to an improvement in filling detector mechanisms for looms.

Both plain and automatic looms are commonly provided with one or more filling detector mechanisms, which determine the presence or absence of the running filling. If the filling is present, the detector mechanism does not affect the loom operation; but if the filling is absent, the detector mechanism effects a change in the operation of the loom, by either initiating the weft replenishing operation or by causing loom stoppage. It sometimes happens that the operation of filling detector mechanisms, as they have heretofore been constructed, is defective, that is to say, sometimes a change in the operation of the loom is effected when the running filling is actually present; and sometimes when the filling is absent the change in the loom operation is not effected immediately, but is unnecessarily delayed two or more beats.

The object of the present invention is to produce a filling detector mechanism of such construction and arrangement of parts that the operation of detecting the presence or absence of the running filling will be accurately performed, so that a change in the loom operation will not be effected unless the filling is actually absent, and so that in case the filling is absent, the necessary change in the loom operation will be effected immediately and without unnecessary delay. To the accomplishment of this object and such other objects as shall hereinafter appear, the present invention consists in the improved filling detector mechanism described in the following specification and particularly pointed out in the appended claims.

The preferred form in which it is contem-

plated embodying the invention is illustrated in the accompanying drawings, in which Figure 1 is a side elevation, partly in section, of the improved filling detector mechanism, showing its relation with certain coöperating parts of the loom; Fig. 2 is a sectional elevation on an enlarged scale of the rear or left-hand end of the parts shown in Fig. 1, showing particularly the improvements of the present invention; Fig. 3 is a section taken on the line 3—3 of Fig. 2; Fig. 4 is a plan of the filling fork alone; and Fig. 5 is a rear end elevation thereof.

The filling detector mechanism of the present invention comprises a filling fork, generally indicated at 5, which, although radically differing in construction from the filling forks of prior filling detector mechanisms, performs the same function, namely, the detection of the presence or absence of the running filling. For this purpose the filling fork 5 is pivotally mounted on a detector slide 6 and is provided with downwardly extending filling engaging members or fork tines 7 which coöperate with the grid 8 mounted on the lay 9. The fork is further provided with a fork tail or bail 10 which cooperates, when the filling is absent, with the hook 11 pivoted at 12 on the weft hammer 13. When the shuttle 15 on its flight through the shed leaves a filling thread in the shed and in front of the grid 8, the latter on its forward movement with the lay 9 presses the filling against the fork tines 7, thereby tilting the filling fork and raising the fork tail 10 out of the path of motion of the weft hammer hook 11 so that the cross bar 16 on the fork tail may not be engaged by the shoulder 17 on the weft hammer hook. But when the shuttle fails to lay filling in front of the grid, the filling fork is not tilted and thereupon the shoulder 17 of the weft hammer hook engages the cross bar 16 of the fork tail, and the detector slide 6 is moved forward with the weft hammer to effect a change in the loom operation by either stopping the loom or by initiating the weft replenishing operation. The forward movement of the detector slide pushes outwardly the arm 18 which is connected with the loom stopping means, or with the weft replenishing mechanism. The detector slide 6 is mounted for sliding movements in a guide-

way 19 secured to the breast beam 20 of the loom. The above-described parts and their attributed functions, with the exception of the filling fork and the grid, are of usual 5 construction and are familiar to those skilled in the art.

When the filling detector mechanism is performing its filling detecting function properly, the filling fork is tilted by the 10 filling, if it is present, on each filling detecting beat-up of the lay, so that the detector slide will remain quiescent. The filling detecting beat-up of the lay is that beat-up which occurs following the boxing of the 15 shuttle at the side of the loom on which the detector mechanism is located. If there is only one filling detector mechanism, every alternate beat-up of the lay will be the detecting beat; but if there are two filling 20 detecting mechanisms, one located on each side of the loom, then every beat-up of the lay is a detecting beat. And so, also, if the filling detector mechanism is performing its function properly, the filling fork will be in 25 such position on a detecting beat that its fork tail will be engaged by the weft hammer hook, if the filling be absent, on the corresponding forward movement of the weft hammer. But the filling detector mechanisms, as heretofore constructed, do not 30 always functionate properly, as hereinbefore set forth; sometimes the weft hammer hook engages the fork tail and moves forward the detector slide to effect 35 an unnecessary change in the loom operation, even though the filling is present; and sometimes, when the filling is absent, the weft hammer hook does not engage the fork tail on the forward movement of the 40 weft hammer corresponding to the detecting beat on which the filling is first absent, with the result that the loom stoppage or the weft replenishing operation is unnecessarily delayed. It has frequently been proposed, 45 heretofore, to eliminate this defective functioning of the filling detector mechanism, and numerous more or less successfully operating devices have been produced. Many of the more successful of these devices are 50 quite elaborate and expensive, and for that reason objectionable. The structure of the present invention, by which the above-described defective functioning of the filling detector mechanism is eliminated, is exceedingly 55 simple and inexpensive. This structure consists in a filling fork of such novel construction and arrangement of parts that the fork operates in the same manner whether the filling thread is heavy or light, or whether it is taut or slack. The condition 60 of the filling both as to its size, and also as to its tautness or slackness, is the chief factor to consider in eliminating the defective functioning of the detector mechanism. The present invention eliminates the

defective functioning by producing a filling fork which is uniformly responsive to the filling, whatever its size or condition.

The improved filling fork of the present invention comprises a body portion or yoke 70 22 which is pivoted at 23 on the rear end of the detector slide 6. The fork tines 7 and the fork tail 10 are both carried by this yoke 22. The fork tail 10, which is a U-shaped member of wire, having its cross 75 bar 16 at its front end, is connected with the yoke 22 in the manner very clearly shown in Figs. 2 and 4. The fork tines 7, it will be observed from an inspection of Fig. 2, are situated well forward of the pivot 23 80 upon which the filling fork as a whole has its tilting movements. By locating the fork tines in this position relatively to the fork pivot, the fork tines swing directly upwardly without first dipping, as would be 85 the case were the fork tines located to the rear of the fork pivot. This contributes materially to ease of operation, and is of especial advantage where it is desired for any reason to draw a filling end in front 90 of the fork tines.

This novel location of the fork tines is one feature of the invention. The advantages in locating the fork tines well forward of the fork pivot are many, chief of which 95 are these: First, it is possible to make a successfully operative fork of very light construction. Where the fork tines are located rearwardly of the fork pivot, the fork tail must be heavy enough to more than counter-balance them. In the present construction the weight of the tines themselves aids in returning the fork to normal position. Hence the possibility of a very light construction; second, it is this light construction of the fork which makes it uniformly 100 responsive to all kinds and conditions of filling. And third, substantially the whole weight of the fork being on one side of the fork pivot, and this being the fork tail side, 105 there is practically no tendency of the fork tail to rebound. It is this rebounding of the fork tail, after the fork has been tilted by the filling, which is the chief cause of the defective functioning of the detector 110 mechanism. The elimination of the rebounding of the fork tail eliminates the defective functioning.

A further feature of the invention resides in independently pivoting the fork tines, as 115 at 25 on the yoke, so that they may yield relatively to the fork tail. This construction is of advantage in preventing breakage of the fork in case the shuttle should come to rest immediately behind the filling fork. 120 The action of the filling fork in such a contingency is illustrated by dot and dash lines in Fig. 1. The fork tail 10 is shown as 125 pressing against the reed cap or hand rail 26, and the fork tines, having been struck by 130

the shuttle, are shown as having yielded relatively to the fork tail, thereby preventing both breakage and jamming of the fork. The fork tines are normally held at right angles to the fork tail by means of a coiled spring 27 of light tension. This spring 27 materially aids in securing the uniform tilting action of the filling fork. It is observed, in practice, that when the filling 10 strikes the fork tines, the inertia of the yoke and the fork tail is sufficient to cause the spring to yield slightly before the fork tilts. Thus, since the shock of the advancing filling is not communicated positively to the 15 fork tail but rather is transmitted to it as an even pressure, the fork tail is raised to substantially a uniform height on each detecting beat. Consequently the fork tail descends and strikes substantially the same 20 spot on the inclined surface 28 of the hook; and since there is practically no rebound of the fork tail, there is no liability, either that the fork tail will descend and be engaged by the hook 17 before the weft hammer 25 has moved forward, or that the fork tail will fail to be engaged by the hook on the next forward movement of the weft hammer, in case the filling be then absent.

The lower ends 29 of the filling engaging 30 members or fork tines, as shown in Figs. 3 and 5, are joined together. The rounded portions 30 permit any loop formed around the fork tines to slip off easily so as not to interfere with the proper action of the fork. 35 The middle bars 31 of the grid 8 are cut away at their lower ends, as shown in Fig. 3, to accommodate the joined-together portion of the fork tines.

The filling fork construction of the present 40 invention is believed to be radically new, and an important improvement in the filling detector mechanism art; it will be understood, therefore, that the invention may be embodied in other forms than that shown 45 and described and still be within the spirit of the following claims.

Having thus described the invention, what I claim is:

1. A filling detector mechanism for looms 50 having, in combination, a detector slide, a filling fork pivoted on the slide having a fork tail to coöperate with the weft hammer when the filling is absent to move the

slide, and depending fork tines mounted on the fork to normally lift the fork tail and 55 to abnormally move yieldingly relatively toward the fork tail.

2. A filling detector mechanism for looms having, in combination, a detector slide, a filling fork pivoted thereon, fork tines pivotally mounted on the fork, and an elastic connection between the fork and the tines. 60

3. A filling detector mechanism for looms having, in combination, a detector slide, a filling fork pivoted on the slide having its 65 tines pivotally mounted on the fork and located between the fork pivot and the breast beam of the loom.

4. A filling detector mechanism for looms having, in combination, a detector slide, a filling fork pivoted on the slide having fork 70 tines so positioned with relation to the fork pivot that their filling engaging portion strikes the filling between the fork pivot and the breast beam of the loom and is thereby 75 caused to rise directly upwardly without first dipping.

5. A filling detector mechanism for looms having in combination, a detector slide, a filling fork pivoted on the slide having a 80 fork tail to coöperate with the weft hammer on filling absence, and depending fork tines adapted on filling presence to coöperate with the filling to prevent the coöperation between the fork tail and the weft 85 hammer, said fork tail and fork tines being situated on the same side of the fork pivot.

6. A filling detector mechanism for looms having, in combination, a detector slide mounted to move toward and from the front 90 of the loom, a filling fork mounted on the slide having a fork tail adapted to coöperate with the weft hammer on filling absence to move the detector slide, and depending fork tines mounted on the fork to have a 95 yielding movement toward the fork tail.

7. A filling detector mechanism for looms having, in combination, a detector slide and a filling fork having a yoke pivotally mounted on the slide, a fork tail rigidly secured to the yoke, fork tines pivotally mounted on the yoke, and a spring tending to hold the fork tines in normal relation to the fork tail. 100
